The ornamental design for a blister assembly for the storage and distribution of pills, as shown.

DESCRIPTION

FIG. 1 is a perspective view of the blister assembly according to the present design;

FIG. 2 is a top plan view of the blister assembly from FIG. 1; FIG. 3 is a bottom plan view of the blister assembly from FIG. 1;

FIG. 4 is a side elevation of the blister assembly from FIG. 1; FIG. 5 is a front elevational view of the blister assembly from FIG. 1; and,

FIG. 6 is a rear elevational view of the blister assembly from FIG. 1.
